UNITED STATES PATENT OFFICE.

FREDERICK J. SCHROEDER, OF CLEVELAND, OHIO, ASSIGNOR, BY MESNE ASSIGNMENTS, TO THE DAMASCUS BRAKE BEAM CO., OF CLEVELAND, OHIO, A CORPORATION OF OHIO, (INCORPORATED FEBRUARY 25, 1916.)

THIRD-POINT SUSPENSION-HANGER.

1,190,470.

Specification of Letters Patent. Patented July 11, 1916.

Application filed November 15, 1915. Serial No. 61,660.

To all whom it may concern:

Be it known that I, FREDERICK J. SCHROEDER, a citizen of the United States, residing at Cleveland, in the county of Cuyahoga and State of Ohio, have invented certain new and useful Improvements in Third-Point Suspension-Hangers, of which the following is a specification.

The present invention relates to third point suspension hangers for trussed brake beams, and the object of the invention is to provide such suspension hangers for use on existing brake beams, without the requirement of any special construction of the strut or the tension member bearing, not even as much as the drilling of a single hole therein.

It has been customary, when a third point hanger is required, to provide an eyelet on the solid metal of the brake fulcrum right from the start. This is generally the case when the fulcrums are made of cast material. In many cases, fulcrums which are not provided with such an eyelet from the beginning, are afterward supplied with a third point suspension hanger, either a forging or a casting, which is riveted or bolted to the brake beam fulcrum. This requires some fitting of the brake beam which necessitates the removal thereof to perform the machining. This is entirely unnecessary with applicant's hanger, which can be attached to the brake beam without any preliminary fitting, and without removing the beam from the car.

In the accompanying drawing, one embodiment of the invention has been illustrated.

Figure 1 is a side view of the third point suspension hanger and the appurtenant part 40 of a brake beam on which it is assembled; Fig. 2, a front elevation of the detached hanger; Fig. 3, an end view partly in section of Fig. 1, seen from the left and Fig. 4, is a plan view of the detached hanger.

The fulcrum of the brake-beam here illustrated is provided with two arms 10 and 11 of rectangular cross section and a solid seat 12 for the tension member 13.

The third point suspension hanger is 50 preferably made in one piece from round stock which is bent as illustrated. The middle or saddle portion 14 with the two perpendicular sides 15, 16 form a loop, which is constructed to ride on the top edge

of the fulcrum arm 10 and contact with the 55 protruding side portions of the fulcrum. The sides 15, 16 are continued by the elbows 17, 18, which reach forward so as to support the tension member 13 on either side of the seat 12. Lastly the two ends are bent round 60 to form eyelets 19, 20, which constitute bearings for a bolt or pin connecting the hanger with a suspension rod or chain. It will be noticed, by referring to the plan view, that the distance between the eyelets is less than 65 the width of the loop 14, 15, 16. The center line of the eyelets is on the same level as the axis of the tension member 13 with the parts in working position as seen in Fig. 1.

It has been found most advantageous to 70 so construct the hanger, that the center of gravity of the fulcrum and, as a consequence, of the entire brake beam, falls in the intersection of the central vertical plane between the two eyelets 19, 20, with the horizontal plane through the center line of the eyelets. In this manner the brake beam will be evenly balanced, without any tendency of 75 tilting, one way or another.

In assembling the parts, it will only be 80 necessary to spring the eyelets over the seat 12 to the rear of the tension member 13, to swing the eyelets forward under the tension member until the latter rests in the elbows 15, 16, when the saddle 14 simultaneously 85 seats on top of the brake beam fulcrum. When the hanger subsequently is attached to its suspension rod by means of passing a bolt through the eyelets, the hanger will be firmly secured on the brake fulcrum without 90 any additional bolts, rivets, or clamps, and no machining or fitting whatsoever will be necessary on the brake beam.

Although the hanger has here been shown 95 as made of round section material, other sections such as square, rectangular, hexagonal, etc., might be used equally well.

I claim:—

1. A third point suspension hanger for 100 brake beams comprising a bar of uniform section bent to form a saddle, two elbows and two eyelets in such a manner that the saddle rides on top of the brake beam, while the tension member of the brake beam rests in the elbows and the eyelets extend beyond said tension member in the longitudinal direction of the brake beam fulcrum.

2. A third point suspension hanger for 105

brake beams, said hanger comprising a saddle, elbows and eyelets, said saddle and elbows being shaped to firmly engage the fulcrum and the tension member of the brake beam, the eyelets being adapted for attachment to a suspension member.

3. A third point suspension hanger for brake beams, said hanger comprising a saddle, elbows and eyelets, said saddle and 10 elbows being shaped to firmly engage the fulcrum and the tension member of the brake beam, the eyelets being adapted for attachment to a suspension member, said eyelets being positioned beyond the tension member in the longitudinal direction of said 15 fulcrum.

4. A third point suspension hanger for 20 brake beams, said hanger comprising a saddle, elbows and eyelets, said saddle and 25 elbows being shaped to firmly engage the fulcrum and the tension member of the brake beam, the eyelets being adapted for attachment to a suspension member, said eyelets being positioned beyond the tension member in the longitudinal direction of said

fulcrum, and in such a manner that the center of gravity of the brake beam falls in the central vertical plane between the two eyelets with the parts in working position.

5. A third point suspension hanger for 30 brake beams, said hanger comprising a saddle, elbows and eyelets, said saddle and 35 elbows being shaped to firmly engage the fulcrum and the tension member of the brake beam, the eyelets being adapted for 40 attachment to a suspension member, said eyelets being positioned beyond the tension member in the longitudinal direction of said fulcrum, and in such a manner that the center of gravity of the brake beam falls in the 45 intersection of the vertical and horizontal planes which run through the longitudinal axis of the hanger and the center line of the eyelets respectively with the parts in working position.

The foregoing specification signed at Cleveland, Ohio, this 11th day of August, 1915.

FREDERICK J. SCHROEDER.
